REMOTE INPUT/OUTPUT CONSOLE OR SIMILAR ARTICLE

John C. Schulte, Montgomery County, Pa., assignor to
Sperry Rand Corporation, New York, N.Y., a corpora-
tion of Delaware

Filed Feb. 17, 1965, Ser. No. 83,850

Term of patent 3½ years

(Cl. D26—5)

FIG. 1

FIG. 2

FIGURE 1 is a front perspective view of a remote input/output console showing my new design, a portion being broken away for convenience of illustration; and FIGURE 2 is a rear perspective view thereof.

I claim:

The ornamental design for a remote input/output console or similar article, as shown and described.
